UNITED STATES PATENT OFFICE.

GEORGE Y. POCOCK, OF SEATTLE, WASHINGTON, ASSIGNOR TO BOLING AIRPLANE CO., OF SEATTLE, WASHINGTON, A CORPORATION OF WASHINGTON.

FORM OR MOLD FOR MAKING PONTOONS.

1,295,203.

Specification of Letters Patent. Patented Feb. 25, 1919.

Application filed April 10, 1918. Serial No. 227,832.

To all whom it may concern:

Be it known that I, GEORGE Y. Pocock, a subject of the King of England, and resident of the city of Seattle, county of King, and State of Washington, have invented certain new and useful Improvements in Forms or Molds for Making Pontoons, of which the following is a specification.

My invention relates to a mold or form which is designed to be used in securing the exterior skin of a pontoon or boat structure, whereby this work may be rapidly done and with certainty of securing proper form in the finished product.

The object of my invention is to reduce the labor cost of doing this work and to insure a more perfect product.

One of the objects of my invention is to provide a mold from which the completed product may be readily removed.

In the drawings I have shown a construction which is now preferred by me for this purpose.

Figure 1 is a top plan view and Fig. 2 a side view of the completed mold.

Fig. 3 is a vertical, longitudinal section, taken at one side surface of the central vertical web of the supporting base, the frame of the pontoon being shown in place.

Fig. 4 is a transverse section.

The mold, as herein shown, is intended for use in building the exterior skin of a pontoon intended for use upon hydroaeroplanes. The general shape of this pontoon resembles a section cut from a cylinder, the cut extending a little to one side of the central line so as to include at its larger part, a little more than half of the cylinder.

In constructing a pontoon of this sort an inner frame work is employed which contains longitudinal members, one of which 7, consists of a board which, in the device illustrated, lies in a central longitudinal plane and others, as 70, consist of bars which extend along the edge of the flat or bottom side of the pontoon, this corresponding in its position somewhat to the position of the gunwale of a boat. In addition, this skeleton frame employs transverse bulkheads 71 and frame members. Consequently, if, as is applicant's practice, the frame work is assembled before applying the outer skin, the mold for receiving the same must have a longitudinal slot for receiving the central web and transverse slots receiving the trans-

versely extending members of the frame. Where circumferential ribs are used, grooves, as 63, 64, for receiving these must be provided.

The mold is constructed upon a fixed base 60 or trestle 1 which is provided with longitudinal and transverse members designed to give it stiffness and rigidity. These members comprise a central plank or web 10 which is placed on edge, and other planks 11, which are placed in horizontal planes, as well as suitable supporting legs. This frame work also includes certain vertical planks 12 and 13 upon which are placed staves 14, which outline the form of the 70 mold upon which the skin is to be shaped.

These parts, as mentioned, form a structure rigid with a base 1, and the upper portion thereof, forming the mold proper, is provided with transverse slots 6, 60, 61, and 75 62, and any other grooves or slots which may be required, as the grooves 63, 64, to admit the structure of the pontoon frame. The central web 10 is preferably so shaped on its upper edge as to form a support for 80 the central web or frame portions of the pontoon frame. The side bars 70 of the pontoon frame may also be supported by bars or strips 72 which are secured to the planks or vertical members 12 of the mold. 85 In Fig. 3 the frame work of the pontoon structure is shown in place. The particular structure of this frame work, aside from the features mentioned, may vary as desired or necessitated by the requirements of the completed product. 90

The design of the pontoon for which the mold herein shown has been planned, contains strips 70 which extend along the lower edge thereof and lie inside of the skin of the 95 pontoon. In consequence, any mold which is designed to form a bearing for the skin while being applied to the frame, must have a member, or members, which extend over this strip. To secure this result and yet to permit ready removal of the pontoon after the skin has been applied, I provide flat vertical surfaces at the side of the mold sections which are of such a width as to 100 permit free application and removal of the frame of the pontoon and supplement the mold by applying at this point, loose sections 3 of such size and shape as to fill 105 out the contour of the mold.

As stated, the mold is transversely sepa- 110

rated by the slots 6, 60, 61, and 62, and such other slots or grooves, as 63, 64, as may be required to permit the passage or embedding of the frame members. This divides the form into short sections, 20, 21, 22, 23, and 24. The loose sections 3 are also divided into short lengths to correspond. When in place, these rest upon the marginal strips 70 of the pontoon frame 10 and when the completed pontoon is removed, these are raised with the pontoon and then removed therefrom.

All of these sections of the mold over which the skin is bent in order to shape 15 it, are provided with an exterior metal surface consisting of plates 5, so that, in forming the skin, brads or tacks may be driven at any point desired and will be clenched on the inside.

20 The type of construction contemplated for this skin is two layers of veneer which are extended diagonally in opposite directions. The inner layer is nailed to the members of the frame and the outer layer, in 25 addition, is nailed to the inner layer at regular intervals, all over its surface. These latter nails will be automatically clenched by contact of the nails with the interior surface of the mold.

30 By the use of a mold of this sort the skin may be applied to the frame rapidly, without requiring the services of highly specialized experts. At the same time, the shape is uniform and may be secured without re-

quiring special care. Also, the frame is held in uniform and fixed position so that when the work is done, the shape of the finished product is uniform and true.

What I claim as my invention is:

1. A mold for use in applying the outer 40 skin of boat-like structures comprising a form having slots therein to receive the inner frame of the boat structure and having loose slab-like sections at the sides adapted to lift off with the completed shell. 45

2. A mold for use in applying the outer skin of boat-like structures comprising a form having slots therein to receive the inner frame of the boat structure and having loose slab-like sections at the sides 50 adapted to lift off with the completed shell, the exterior surface of the mold sections being metal faced to form nail-clenching surfaces.

3. A mold for use in applying the outer 55 skin of boat-like structures comprising a form having an exterior outline conforming to the interior outline of the shell, said form being slotted transversely and longitudinally to receive the corresponding members of the boat frame, and having loose 60 slabs at its sides adapted to fit inside the gunwale member of the boat frame and to lift off with the boat structure.

Signed at Seattle, Washington, this 30th 55 day of March, 1918.

GEORGE Y. POCOCK.

It is hereby certified that the assignee in Letters Patent No. 1,295,203, granted February 25, 1919, upon the application of George Y. Pocock, of Seattle, Washington, for an improvement in "Forms or Molds for Making Pontoons," was erroneously described and specified as "Boling Airplane Co.," whereas said assignee should have been described and specified as *Boeing Airplane Co.*, as shown by the records of assignments in this office; and that the said Letters Patent should be read with this correction therein that the same may conform to the record of the case in the Patent Office.

Signed and sealed this 21st day of October, A. D., 1919.

[SML.]

M. H. COULSTON,

Acting Commissioner of Patents.
